UNITED STATES PATENT OFFICE

SAMUEL MORSE, OF NEW YORK, N. Y.

SPEED REDUCING MECHANISM FOR TRAINING CYCLES

Application filed December 7, 1929. Serial No. 412,549.

This invention relates to speed reducing mechanism for training cycles, and more particularly to that type of mechanism which permits of a very slow forward movement of the cycle when the propelling means is operated at a relatively high speed.

The principal object of this invention is to provide a mechanism which will make it feasible to use uni-cycles, bicycles, motor cycles and the like in places where the space is restricted, without changing the essential character of the cycles and without necessitating any alteration in the propelling mechanism.

15 It is a further object of this invention to provide a speed reducing mechanism which will allow a slow rotation of the traction wheel of the cycle and a resulting slow forward movement of the cycle when the propelling mechanism is operated at a speed which would result in a rapid forward movement of the cycle if the traction wheel were geared to the propelling mechanism in the manner now commonly employed.

20 25 It is still a further object of this invention to provide a mechanism of the type described which may be readily attached to the ordinary bicycle, motor cycle or the like, without necessitating any material changes in the construction of such apparatus.

It is another object of this invention to provide means in connection with the speed reducing mechanism for rendering the same inoperative in order that when desired the 30 35 traction wheel may be connected to the propelling mechanism in the usual manner so that the cycle may be used with the speed reducing mechanism or with the usual type of drive between the propelling mechanism and the traction wheel by merely making a quick adjustment of some of the parts.

Bicycle racers frequently have no indoor or outdoor track accessible for training purposes and it is impracticable or impossible 40 45 for them to do their training on the highway due to congested traffic conditions and unfavorable weather. It is, therefore, necessary that they train in restricted areas which would ordinarily require them to ride at a slower speed than when they were actually

racing. Obviously this puts them at a disadvantage by reason of the fact that unless they are able to do their training under operating conditions substantially the same as those under which they race, that is, unless they can propel their machines at a rate of speed corresponding to that which they must attain in racing, the benefits to be derived from their training will necessarily be limited.

It is furthermore often desirable to hold actual races in gymnasiums, athletic clubs or other places where only a small area is available for such purpose. In addition, it is often desirable to use bicycles on theater stages. Under any of these conditions, due to the restricted area available, it is necessary that the cycle move forward at a relatively slow speed.

I am aware that it has hitherto been proposed to solve the difficulty above suggested by mounting the bicycle in a stationary frame so that the rider may propel the machine at any rate of speed he desires. Such type of training apparatus, however, is disadvantageous in that the conditions under which he races are not present in that the machine itself does not move, and as a consequence there is no need for steering or balancing the machine. I am also aware that it has hitherto been proposed to provide a pair of small wheels in a framework which is attached to the rear or traction wheel of a bicycle and which are driven by the traction wheel through a suitable speed reducing mechanism. Such a device also has the disadvantage that the bicycle is no longer such, but in nature becomes a tricycle, so that the rider, while actually moving forward, does not have to balance the machine and he must negotiate turns in a manner different from that which would be followed if the machine were actually a bicycle.

It is therefore my purpose to provide a 95 training cycle which may be used in a small space due to the slow speed at which it moves and which will, moreover, accomplish this end without affecting the essential character of the cycle and without changing the 100

conditions which would be met if the cycle were operated at ordinary speeds.

Briefly stated, my invention consists in a speed reducing mechanism which is interposed between the propelling mechanism and the traction wheel of the cycle.

While I have described my invention in connection with a bicycle, it is to be understood that it may be used in connection with a motor cycle or any similar machine. In the accompanying drawings I have illustrated a practical embodiment of my invention, but it is to be understood that the drawings are merely illustrative and are in no way to be considered as limiting the invention to the details of construction therein set forth. It will be obvious to those skilled in the art that the invention is susceptible of embodiment in forms other than that shown, without departing from the scope of the invention as set forth in the accompanying claims.

In the drawings:

Fig. 1 shows my speed reducing mechanism adapted to a bicycle having the common foot-propelling mechanism. The figure shows a plane vertical view of my speed reducing mechanism in connection with the rear or traction wheel of the bicycle, the propelling means and that portion of the bicycle frame with which these mechanisms are associated.

Fig. 2 is a plane end view of the mechanism shown in Fig. 1.

Fig. 3 is a detailed sectional view showing the construction of the hub of the traction wheel, the mounting of the gears which form a portion of my speed reducing mechanism and the means for directly connecting the traction wheel to the sprocket which is driven directly by the foot-operated propelling means.

Fig. 4 is a detailed view of a portion of my speed reducing mechanism, together with a portion of the frame in which it is slidably mounted.

Referring now to the drawings, the reference numeral 10 indicates a traction wheel of a bicycle which is rotatably mounted on an axle 11 mounted in the bicycle frame 12. Reference numeral 13 indicates the ordinary foot-propelled sprocket which constitutes the propelling means for the bicycle. The propelling means drives a sprocket 14 rotatably mounted on the axle 11 through a chain drive 15. The essential parts of my speed reducing mechanism comprise a large gear 16 which is rotatable with the sprocket 14, intermediate gears 17 and 18 rotatably mounted on an axle 19, said axle being adjustably mounted to slide in slots 20 in the frame members 21, and a ring gear 22 associated with the periphery of the traction wheel. It will be evident that when my speed reducing mechanism is being em-

ployed, the propelling sprocket 13 will drive the gear 16, which in turn drives the traction wheel through the intermediate gears 17 and 18. It will be evident that I may design my speed reducing means to drive the traction wheel at any desired rate of speed for a propelling sprocket of any given size, by changing the relative size of the gears 16, 17 and 18.

Referring to Fig. 3, the reference numeral 23 denotes the hub of a traction wheel 10, rotatably mounted on the axle 11. Rotatably mounted on the same axle 11, but having separate hubs 24 and 25 respectively, are the speed reducing gear 16 and the sprocket 14. In order that the traction wheel may be driven directly by the propelling means through the sprocket 14, I have provided an annular groove 26 in the hub 24 of the gear 16 which rotates with the hub 25 of the sprocket 14 in which groove rides an annular flange 27 which forms a projection upon and at right angles to the flange 28 of the traction wheel hub 23. To gear the sprocket 14 to the traction wheel, it is only necessary to drop the pins 29 into suitable recesses provided in the hub 24 and in the flange 27. It will, of course, be understood that when the traction wheel is being driven directly through the gear 14, the speed reducing mechanism which operates through the ring gear 22 on the periphery of the wheel must be rendered inoperative. This is accomplished by mounting the axle of the intermediate gears 17 and 18 to slide in the slots 20 in the frame members 21, thus enabling the axle to be slid upwardly in the frame members to disengage the gears 17 and 18 from the gears 16 and 22 respectively. In order that the axle 19 may be secured in any desired position with respect to the slots 20 in the frame members, any suitable locking means may be used, such as thumb screws.

When it is desired to use my speed reducing mechanism in connection with a bicycle, the pins 29 will be removed so that the traction wheel will be rotatable independent of the sprocket 14 and the gear 16, and the gears 17 and 18 will be engaged with the gears 16 and 22 respectively. With this arrangement, it will be evident that the traction wheel 10 will rotate at a speed very much less than the speed of rotation of the sprocket 13, due to the relatively large diameters of the gears 16 and 22 with respect to the diameter of the sprocket 13. When it is desired to operate the bicycle without the speed reducing mechanism, the gears 17 and 18 will be disengaged from the gears 16 and 22 by sliding the axle 19 upwardly in the slots 20 in the frame members and the pins 29 will be dropped into place to gear the sprocket 14 to the traction wheel hub 23.

I claim:

1. In a training cycle, a driving sprocket

and a wheel mounted therein, speed reducing means gearing said wheel to said sprocket, and means for rendering said speed reducing means inoperative.

5. 2. In a training cycle, a driving sprocket and a wheel mounted therein, speed reducing means mounted independently of the mountings of the wheel gearing said wheel to said sprocket, and means for rendering 10 said speed reducing means inoperative.

3. In a training cycle, a driving sprocket and a wheel mounted therein, said wheel and said sprocket being rotatably mounted on a common axle, speed reducing means 15 gearing said sprocket to said wheel, and means for rendering said speed reducing means inoperative.

4. In a training cycle, a driving sprocket and a wheel mounted therein, speed reducing means gearing said sprocket to the periphery of said wheel, and means for rendering said speed reducing means inoperative.

5. In a training cycle, a driving sprocket 25 and a wheel mounted therein, speed reducing means mounted independently of the mountings of the wheel gearing said sprocket to the periphery of said wheel, and means for rendering said speed reducing means 30 inoperative.

6. In a training cycle, a driving sprocket and a wheel mounted therein, speed reducing means for gearing the wheel to the sprocket, and means for effecting a direct 35 drive between the wheel and the sprocket.

7. In a training cycle, a driving sprocket and a wheel mounted therein, speed reducing means mounted independently of the mountings of the wheel for gearing the 40 wheel to the sprocket, and means for effecting a direct gearing between the sprocket and the wheel.

8. In a training cycle, a driving sprocket and a wheel mounted therein, said wheel and said sprocket being rotatably mounted 45 on a common axle, speed reducing means for gearing said wheel to said sprocket, and means for effecting a direct drive between the wheel and the sprocket.

50. 9. In a training cycle, a driving sprocket and a wheel mounted therein, speed reducing means for gearing said sprocket to the periphery of said wheel, and means for effecting a direct drive between the sprocket 55 and the wheel.

10. In a training cycle, a driving sprocket and a wheel mounted therein, speed reducing means mounted independently of the mountings of the wheel for gearing the 60 sprocket to the periphery of the wheel, and means for effecting a direct drive between the sprocket and the wheel.

65. 11. In a training cycle, a driving sprocket and a wheel mounted therein, speed reducing means for gearing the wheel to the

sprocket, means for rendering said speed reducing means inoperative, and means for effecting a direct drive between the sprocket and the wheel.

12. In a training cycle, a driving sprocket 70 and a wheel mounted therein, speed reducing means mounted independently of the mountings of the wheel for gearing the wheel to the sprocket, means for rendering said speed reducing means inoperative, and means for effecting a direct drive between 75 the sprocket and the wheel.

13. In a training cycle, a driving sprocket and a wheel mounted therein, speed reducing means for gearing the sprocket to the 80 periphery of the wheel, means for rendering said speed reducing means inoperative, and means for effecting a direct drive between the sprocket and the wheel.

14. In a training cycle, a driving sprocket 85 and a wheel mounted therein, a gear having a diameter of a magnitude approximating that of the wheel rotatable with said sprocket, and means for effecting a driving connection between said gear and the periphery of the wheel.

In testimony whereof, I affix my signature.

SAMUEL MORSE.
